UNITED STATES PATENT OFFICE.

WILLIAM W. LEWIS, OF GARNET, WEST VIRGINIA.

DUMPING-GRAVE.

1,082,127.

Specification of Letters Patent.

Patented Dec. 23, 1913.

Application filed February 16, 1912. Serial No. 677,942.

To all whom it may concern:

Be it known that I, WILLIAM W. LEWIS, a citizen of the United States, residing at Garnet, in the county of Kanawha and State 5 of West Virginia, have invented a new and useful Dumping-Grate; and I do hereby declare the following to be a full, clear, and exact description of the invention, such as will enable others skilled in the art to which 10 it appertains to make and use the same.

This invention relates to a new and useful grate.

It is the object of this invention to produce a device of this design, in which simple, efficient, practical and desirable features 15 of construction are involved.

One of the features of the invention resides in a grate, which may be easily manipulated, so as to dump the fire, and shaken 20 to remove the ash.

Another feature is the provision of a lock to hold the grate in a horizontal position.

The invention comprises further features and combination of parts, as hereinafter set 25 forth, shown in the drawings and claimed.

In the drawings:—Figure 1 is a longitudinal sectional view through a fire box of a range, showing the improved grate as applied. Fig. 2 is a cross sectional view on 30 line 2—2 of Fig. 1. Fig. 3 is a detailed view of the means for operating the grate, and also the locking means for the operating means. Fig. 4 is a detail view of a portion 35 of the grate, showing the connection of the lever 14 therewith.

Referring more essentially to the drawings, 1 designates the frame for the side grate bars 2, the latter being connected to the bars 3 and 4 of the frame 1. Projecting 40 inwardly of the fire box, and from the frame 1 is a supplemental frame 5, the end and longitudinal bars of which are connected by dove-tailed joints 6. Each of the end bars of the supplemental frame is provided with 45 an aperture 7. Mounted in the apertures are the pintles 8 of the tilting grate 9. One of the pintles of the tilting grate is formed with a rectangular portion 10, which is arranged in the opening 11 of the arm 12. 50 This arm 12, by this construction works rigidly with the tilting grate, and is disposed

between one of the end bars and the grate. Pivoted to the lower end of this arm, as at 13 is a lever 14. This lever 14 passes through an opening in the lower bar of the 55 frame 1, and is provided with a notch 14^a. The opening is denoted by the numeral 15. Pivotedly mounted as at 16 to the lower bar of the frame is a latch 17, adapted to engage the notch of the lever, to hold the tilt- 60 ing grate in a horizontal position. When it is desired to tilt the grate, in order to dump the fire, or remove the clinkers, the latch is raised from engagement in the notch, and subsequently the lever is reciprocated. 65 One end of the tilting grate is formed with a shoulder 18, which contacts with the lever 14 to limit the grate in its pivotal movement in one direction, that is, when the grate is being rattled, so as to only stir the 70 fire. In rattling or shaking the grate, the lever is reciprocated slightly, in other words, not enough to dump the fire. In this way the body of the fire is not lost. The shoulder on the tilting grate limits the same in 75 its movement in the other direction.

From the foregoing it will be noted, there has been devised a novel, simple, and practical tilting grate, adapted mainly for use in connection with ranges and the like. 80

Coupled to the lever as at 19 is an arm 20, which is adapted to be swung downwardly, when the grate is at rest. This arm is designed for the purpose of operating the lever 14. 85

The invention having been set forth, what is claimed as new and useful is:—

In combination with a fire-box having vertical front grate bars, said front grate bars being provided with a lower bar and having 90 a laterally projecting frame arranged horizontally in the fire-box, of a tilting grate having a pintle at each end journaled in each end of said lateral frame, one of said pintles having a rectangular portion, an arm 95 having an opening fitting the rectangular portion, said arm being held on the rectangular portion between one end of the tilting grate and one end of the lateral frame, and a lever mounted in the lower bar of the front 100 grate bars and connected to the lower end of said arm for rocking the tilting grate,

the tilting grate having a shoulder alined with said lever so as to engage the lever when the grate is rocked, to limit the same in its pivotal or rocking movements, and a member pivoted on said lever for manipulating the latter whereby the tilting grate may be oscillated.

In testimony whereof I have signed my name to this specification in the presence of two subscribing witnesses.

WILLIAM W. LEWIS.
